UNITED STATES PATENT OFFICE.

ISRAEL DICKSTEIN AND BENJAMIN A. SHINDELL, OF NEW HAVEN, CONNECTICUT, ASSIGNORS TO CONNECTICUT CONE CO., INC., OF NEW HAVEN, CONNECTICUT, A CORPORATION.

DESIGN FOR AN ICE-CREAM CONE.

Application filed July 19, 1923. Serial No. 6,805. Term of patent 3½ years.

To all whom it may concern:

Be it known that we, ISRAEL DICKSTEIN and BENJAMIN A. SHINDELL, citizens of the United States, residing at New Haven, in the county of New Haven and State of Connecticut, have invented a new, original, and ornamental Design for an Ice-Cream Cone, of which the following is a specification, reference being had to the accompanying drawing, forming part thereof.

We claim:

The ornamental design for an ice cream cone as shown.

ISRAEL DICKSTEIN.
BENJAMIN A. SHINDELL.

Witnesses:

FREDERIC C. EAM,
MALCOLM P. NICHOLS.
